CLAIM

The ornamental design for a computer host as shown and described.

DESCRIPTION

FIG. 1 is a front, right, and top perspective view of computer host, showing my new design;
FIG. 2 is a rear, left, and bottom perspective view thereof;
FIG. 3 is a front elevational view thereof;
FIG. 4 is a rear elevational view thereof;
FIG. 5 is a left elevational view thereof;
FIG. 6 is a right elevational view thereof;
FIG. 7 is a top plan view thereof; and,
FIG. 8 is a bottom plan view thereof.
The broken lines in the drawings depict portions of the computer host that form no part of the claimed design.
